UNITED STATES PATENT OFFICE.

ALBERT J. HORTON, OF WHITE PLAINS, NEW YORK, ASSIGNOR TO THE CUTLER-HAMMER MFG. CO., OF MILWAUKEE, WISCONSIN, A CORPORATION OF WISCONSIN.

MOTOR-CONTROLLER.

1,163,150.

Specification of Letters Patent.

Patented Dec. 7, 1915.

Application filed September 12, 1914. Serial No. 861,445.

To all whom it may concern:

Be it known that I, ALBERT J. HORTON, a citizen of the United States, residing at White Plains, in the county of Westchester and State of New York, have invented new and useful Improvements in Motor-Controllers, of which the following is a full, clear, concise, and exact description, reference being had to the accompanying drawing, forming a part of this specification.

This invention relates to improvements in circuit controllers.

In my Patent No. 1,122,931, granted Dec. 29, 1914, there is disclosed a controller for motor driven printing presses and other apparatus, wherein a two-push-button control station provides for inching, for continued operation at different speeds, and for stopping at will, and the present invention has among its objects to provide a two-push-button station operable to accomplish the foregoing and also lockable to insure against starting.

Various other objects and advantages of the invention will hereinafter appear.

One embodiment of the invention is illustrated in the accompanying drawing, which will now be described.

In the drawing, Figure 1 illustrates the controller diagrammatically and, Figs. 2 and 3 illustrate in front elevation and vertical section a mechanical embodiment of the push-button station diagrammatically illustrated in Fig. 1.

Referring to Fig. 1 the same shows an electric motor M, an electro-responsive switch S controlling the continuity of the motor circuit, an electromagnetically operated rheostat R for accelerating the motor and a two-push-button control station S' for controlling the switch S and rheostat R. The motor M has for the purpose of illustration been shown as having an armature A and a series field winding F, it being understood that any preferred type of motor may be employed. The switch S and rheostat R are both of conventional form. The switch S is provided with a normally open auxiliary switch 5 adapted to be closed upon response of said switch S. The rheostat R is provided with switch arms 6, 7, and 8 operable by a solenoid 9 to successively engage cooperating stationary contacts to gradually exclude the resistance r from the motor cir-

cuit. The push-button control station includes two switches 10 and 11. The switch 10 has two contact disks 12 and 13, the former to bridge stationary contacts 14 and the latter to bridge stationary contacts 15. As will hereinafter appear, either of the disks 12 may be disengaged from its respective stationary contacts by operation of a common push-button 16. Also, either disk may be positively locked out of engagement with its contacts by an adjustment of push-button 16. The switch 11 has a contact disk 17 adapted in one position to bridge contacts 18 and in another position to bridge contacts 19. As will hereinafter appear, engagement of the disk 17 with either set of its co-operating contacts may be effected by operation of a push-button 20 and by an adjustment of said push-button, said disk may be locked out of engagement with contacts 18.

Referring now to Fig. 3, both push-button switches are inclosed in a casing 21, their stationary contacts being mounted upon an insulating base 22 fixed to the rear wall of said casing. In practice the two sets of contacts of each switch are arranged at right angles and in consequence Fig. 3 shows only one contact of each set. Referring specifically to switch 10 the push-button 16 thereof is reciprocably mounted in the front wall of the casing and has a stem 23 reciprocable in a bearing 24 on the rear wall of the casing. Both disks 12 and 13 are loosely mounted upon the stem 23 and are normally spread apart to engage their respective contacts by an interposed spring 25. The stem 23 also has mounted thereon and fixed thereto, to the rear of the disk 13, a collar 26 and interposed between this collar and the rear wall of the casing is a second spring 27 of greater strength than the spring 25. The pushbutton 16 by an abutment with the contact disk 12 provides for disengaging said disk from its contacts 14 while the spring 27, when permitted to force the collar 26 against the disk 13, provides for disengaging said disk from its contacts 15. The normal positions of the contact disks and the effect of depression of the push-button are governed by radial stops 28 and 29 on the push-button and a radial slot 30 through the front wall of the casing. The pins 28 and 29 are angularly disposed with respect to one another and are arranged at spaced points longitudi-

nally of the push-button to function as follows: When the pin 29 engages the rear face of the casing wall as shown in Fig. 3, it holds the push-button in a semi-depressed position, spacing the collar 26 from the disk 13 and thereby relieving said disk of the pressure of spring 27. Under such conditions the disks 12 and 13 are normally maintained in engagement with their respective contacts by the spreading spring 25 subject to disengagement of disk 12 from its contacts 14 by further depression of the push-button 16 and to return by the spring 25. Assume now that the push-button 16 be rotated to aline the pin 29 with the slot 30, then the push-button would be released for full outward movement and the spring 27 would force the collar 26 against the disk 13, thereby normally holding said disk out of engagement with contacts 15 subject to re-engagement by depression of push-button 16. Again assume that the push-button be held in semi-depressed position, as aforesaid, then the disk 12 might be locked out of engagement with its contacts 14 by alining pin 28 with slot 30, then depressing the push-button 16 to the full extent and then turning said push-button until pin 28 engages the rear face of the casing wall.

Referring now to switch 11 the push-button 20 thereof is provided with a stem 31 and is mounted in the casing similarly to switch 10. Its disk 17 is loose upon the stem 31 and is held by means of a spring 32 against a collar 33 fixed to said stem. The collar 33 in turn is biased outwardly by a spring 34 similar to the spring 27. Thus the arrangement is such that the spring 34 tends to force the disk 17 into engagement with its contacts 18 subject to disengagement therefrom and engagement with its contacts 19 by depression of pushbutton 20. The push-button 20 has two radial spaced pins 35 and 36 coöperating with two radial slots 37 and 38 in the front wall of the casing, as best illustrated in Fig. 2. As illustrated in Fig. 3, pin 36 engages the rear face of the casing wall holding the push-button in a semi-depressed position, thereby disengaging the disk 17 from its contacts 18. Under such conditions, with the pin 35 alined with the slot 37 the button 20 may be depressed to move the disk 17 into engagement with its contacts 19 and when the push-button is released the spring 34 restores said disk to the position illustrated. The disk 17 may, however, be freed for engagement with contacts 18 by rotating the push-button 20 until the pins 35 and 36 both aline with the slots 38 and 37 respectively, whereupon the spring 34 will force the push-button outwardly until the aforesaid engagement of said disk is effected. Then the push-button 20 may be depressed to move the disk 17 out of engagement with contacts 18 and into engage-

ment with contacts 19 subject to automatic return of said disk by spring 34 into engagement with said contacts 18.

With the foregoing operations of the push-button station in mind it will be observed that the following control of the motor may be effected: Assume first that the switches are set to normally stand in the positions illustrated. The motor may be started and accelerated by depression and release of switch 11. Depression of the switch 11 completes circuit from line L by conductor 40 through the operating winding of switch S, by conductor 41 through the contacts 12 and 14 of switch 10, by conductor 42 through the contacts 17 and 19 of switch 11, by conductor 43 to line L'. This causes response of switch S which completes the motor circuit from line L by conductor 44 through the resistance r of rheostat R, by conductor 45 through the motor armature A and series field winding F, by conductor 46 to line L'. The motor is thus started and as soon as the switch 11 is released the solenoid 9 is energized to operate the rheostat R and thus exclude the resistance r from the motor circuit. The circuit of solenoid 9 may be traced from conductor 44 by conductor 47 through said solenoid, by conductor 48 through the contacts 17 and 18 of switch 11, by conductor 49 through the auxiliary switch 5 of main switch S, by conductor 50 to line L'. Of course, release of the switch 11 to accelerate the motor interrupts the energizing circuit of the main switch but as soon as the main switch responds, it establishes its own maintaining circuit from conductor 42 through contacts 13 and 15 of switch 10, by conductor 51 through a suitable resistance r' , by conductor 52 through auxiliary switch 5 and by conductor 50 to line L'. Thus, as above stated, depression and release of the switch 11 effects starting and acceleration of the motor. Assume now that it is desired to start the motor for operation at slow speed, then prior to starting the switch 11 is adjusted to lock the disk 17 out of engagement with contacts 18. This still enables the motor to be started by depression of the push-button 20 as above described but upon release of the push-button limits the movement of the disk 17 to prevent energization of the solenoid 9 of the rheostat R.

For stopping the motor when started, as above described, the switch 10 is operated by depression of its push-button 16 to disengage disk 12 from contacts 14. Disk 12, and contacts 14 are included in the maintaining circuit of the switch S and hence upon separation deenergize said switch and accordingly stop the motor. In the event that the solenoid 9 is energized when the motor is stopped then the switch S through its auxiliary switch 5 disconnects said solenoid

from circuit whereby the rheostat R is insured return to initial position for restarting of the motor.

Assume now that it is desired to inch, the 5 switch 10 is first set to disengage its disk 13 from contacts 15 thereby interrupting the maintaining circuit for the main switch S and then the motor is started by depression of push-button 20 of switch 11, as above described. Under these conditions it will be observed that inasmuch as the main switch S is deprived of its maintaining circuit the push-button 20 must be manually depressed as long as it is desired to maintain the motor 10 in operation and that as soon as this button is released the main switch will be deenergized and the motor immediately stopped.

Assume now that it is desired to inspect or repair the apparatus driven by the motor 15 and to insure against unexpected starting during such inspection or repair. This may be accomplished by adjustment of the switch 10 as above described to lock the contact disk 12 out of engagement with contacts 14. 20 This disk and its contacts, as will be noted, are in the energizing circuit of the main switch S between said switch and the starting switch 11 so that obviously when the switch 10 is set as described the switch 11 25 will be ineffective to start the motor. In practice it is quite customary to provide a number of push-button stations whereby the motor may be controlled as above described from any one of the same, and in such cases 30 it will be obvious that by connecting the contacts 14 and disk 12 of all stations in series in the energizing circuit of the main switch, lockout of any one of the disks 12 will render all stations temporarily ineffective for starting.

What I claim as new and desire to secure by Letters Patent is:

1. In a motor controller, the combination with electro-responsive starting means, of a control station therefor including two push-button switches one operable to effect starting and the other operable to effect stopping, said latter switch being adapted to be set in a position to prevent starting by said former switch.

2. In a motor controller, the combination with electro-responsive starting means, of a control station therefor including two push-button switches, one being depressible to effect energization of said means for starting and the other being adapted to be set in different positions to render continued energization of said means either dependent upon or independent of continued depression of said first mentioned switch or to render said first mentioned switch ineffective to energize said means.

3. In a motor controller, the combination with electro-responsive starting means, of a control station therefor including two push-

button switches, one depressible to energize said means for starting and the other depressible to deenergize said means for stopping, said latter switch being also adapted to be set in different positions to render continued energization of said means either independent of or dependent upon continued depression of said first mentioned switch or to render said first mentioned switch ineffective to energize said means. 70

4. In a motor controller, the combination with electro-responsive starting means, of a control station therefor including two push-button switches, one depressible to energize said means for starting and the other being depressible to deenergize said means and lockable in depressed position to render said first mentioned means ineffective for starting. 75

5. In a motor controller, the combination with electro-responsive starting means, of two push-button control switches therefor jointly controlling the energizing circuit of said means whereby said means may be energized by depression of one of said switches 80 when the other is in a predetermined position, said latter switch being adapted to be set in a position to render said former switch ineffective to energize said means. 85

6. In a motor controller, the combination with electro-responsive starting means having an energizing circuit and a maintaining circuit, of two push-button switches jointly controlling the energizing circuit of said means whereby said circuit may be closed 90 when the other is in a predetermined position, said latter switch being adapted to be set in a position to render continued energization of said means dependent upon or independent of continued depression of said first mentioned switch or to render said first mentioned switch ineffective to energize said means. 95

7. In a motor controller, the combination with electro-responsive starting means having an energizing circuit and a maintaining circuit, of a push-button operated switch controlling both of said circuits, said switch being depressible to open said energizing circuit and having means to releasably lock the same in depressed position. 100

8. In a motor controller, the combination with electro-responsive starting means having an energizing circuit and a maintaining circuit, of a push-button operated switch adapted to be set in one position to interrupt said energizing circuit or in another position to complete said energizing circuit 105 and interrupt said maintaining circuit. 110

9. In a motor controller, the combination with electro-responsive starting means having an energizing circuit and a maintaining circuit, of a push-button operated switch 115

adapted to be set in one position to interrupt said energizing circuit or in another position to complete said energizing circuit and interrupt said maintaining circuit, or 5 in a third position to complete its respective portion of both of said circuits.

10. In a motor controller, in combination, electro-responsive starting means having an energizing circuit and a maintaining circuit, 10 of a push-button operated switch having a movable contact in said maintaining circuit and a second movable contact common to both said energizing and maintaining circuits, said contacts being operable by a 15 common push-button and being adapted to be set in different positions to interrupt both circuits or to interrupt only said maintaining circuit.

11. In a motor controller, in combination, 20 electro-responsive starting means having an energizing circuit and a maintaining circuit, of a push-button operated switch having a movable contact in said maintaining circuit and a second movable contact common to both said energizing and maintain-

ing circuits, said contacts being operable by a common push-button and being adapted to be set in different positions to interrupt both circuits or to interrupt only said maintaining circuit or to complete their respective portions of both circuits. 30

12. In a motor controller, the combination with electro-responsive starting means having an energizing circuit and a maintaining circuit, of a push-button switch controlling both of said circuits and being adapted to be set in different positions to complete its respective portion of both of said circuits or interrupt either of said circuits and a second push-button switch depressible to 35 energize said means subject to control by said first mentioned switch. 40

In witness whereof, I have hereunto subscribed my name in the presence of two witnesses.

ALBERT J. HORTON.
